UNITED STATES PATENT OFFICE

119,982

DESIGN FOR A PLANT BOWL

John Munz, Jamaica, N. Y.

Application July 27, 1939, Serial No. 86,265

Term of patent 3½ years

To all whom it may concern:

Be it known that I, John Munz, a citizen of the United States, residing in Jamaica, city of New York, county of Queens, and State of New York, have invented a new, original, and ornamental Design for a Plant Bowl, of which the following is a specification, reference being had to the accompanying drawing, forming a part thereof.

Figure 1 is a top plan view of a plant bowl showing my new design.

Figure 2 is an elevational view thereof.

The characteristic feature of the design consists of an opaque base in combination with a transparent dome, as shown in the drawing.

I claim:

The ornamental design for a plant bowl as shown and described.

JOHN MUNZ.
